UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 31,709, dated October 24, 1899.

Application filed March 3, 1899. Serial No. 707,677. Term of patent 7 years.

To all whom it may concern:

Be it known that I, CHARLES J. AHREN-
FELDT, a citizen of the United States, residing
at the city of New York, county of New York,
5 and State of New York, have invented and
produced a new and original Design for a Plate
or Similar Article, of which the following is a
specification, reference being had to the ac-
companying drawings, forming a part hereof,
10 and like letters referring to like parts in each
figure of the same.

In the said drawings, Figure 1 is a plan view
of a plate with my design placed thereon. Fig.
2 is a medial vertical section of the same.

15 In the design upon the plate a pair of roses
A, with leaves B interposed between and pro-
jecting above and below, forms a centerpiece,
from which project on convergent lines at

either side leafed stems C. This ornament
is repeated a number of times, the ornaments 20
being disposed in a circular manner and the
pair of roses in each piece connected to the
adjoining ones by a streamer of forget-me-
nots D, so that the whole forms a band or bor-
der. 25

This design may be applied to articles other
than plates.

What I claim is—

The design for a plate or similar article sub-
stantially as herein shown and described. 30

Signed at the city of New York, in the State
of New York, this 10th day of February, 1899.

CHARLES J. AHRENFELDT.
